LAPPING APPARATUS

David A. Wallace, Detroit, Mich., assignor to
Chrysler Corporation, Highland Park, Mich., a
corporation of Delaware

Original application January 30, 1937, Serial No.
123,119. Divided and this application April
27, 1938, Serial No. 204,572

3 Claims. (Cl. 51—184.3)

This invention relates to an improved apparatus for lapping the surfaces of cylindrical bores and for accurately bringing the latter to true cylindrical contour and is a division of my application, Serial No. 123,119, filed January 30, 1937.

One of the main objects of the invention is to provide an improved expandable lap for lapping cylindrical surfaces.

Other objects of the invention are to provide a device of this character which has a plurality of lapping elements arranged in spaced series and which is adapted to operate simultaneously upon the walls of a plurality of aligned bores in order to accurately bring such walls into concentric relationship with respect to a common axis; to provide means for adjustably supporting a plurality of lapping elements in arcuately arranged relationship so that they may expand and contract in order to accommodate the lap to the finishing of bores of different diameters; to provide means of this kind by which the lapping elements are yieldably urged outwardly toward an adjustably selected predetermined limiting position in order to accommodate operation of the lap in an underside bore and to facilitate lapping thereof to a predetermined diameter; and to provide means in a multiple lap of this character for accurately holding the adjustable lapping elements thereof in alignment with their axis of rotation so that the lap will form the walls of the bore to a true cylindrical contour and the positions of the lapping elements will not be determined by the rough contour of the walls of the bore.

Other objects of the invention are to provide a lap of this kind that has an outer tubular casting which sustains the main portion of the strains and stresses to which the device is subjected in operation and which is provided with an inner surface of comparatively large area that serves as a reference surface for predetermining the positions of the lapping elements and maintaining the same in accurate parallelism with the axis of the tool; and to provide a lapping element adjustment control member in a device of this kind which is relieved of all lapping element supporting functions.

An illustrative embodiment of the invention is shown in the accompanying drawing, in which:

Fig. 1 is a plan view of a lapping tool embodying the invention.

Fig. 2 is an enlarged, fragmentary, central, longitudinal, sectional view taken on the line 2—2 of Fig. 1.

Fig. 3 is an end elevational view taken from the right as viewed in Fig. 1.

Fig. 4 is a transverse sectional view taken on the line 4—4 of Fig. 2.

Fig. 5 is a transverse sectional view taken on the line 5—5 of Fig. 2.

In the form of the invention illustrated in the drawing, the multiple expandable lapping tool, generally designated by the numeral 71, and illustrated in Figs. 1 to 5, inclusive, comprises a tubular casing 97 having a plurality of axially spaced series of circumferentially arranged slots 98 which extend axially of the casing. Radially slidably mounted in each slot 98 is a lapping member comprising a lapping element, preferably including either natural or compressed stone 99 and a lapping element carrier 100 having a groove in its outer side in which its lapping element is securely mounted. The lapping elements may comprise either natural or artificial stone or any suitably lapping abrasive, or polishing material. The lapping element carriers 100 taper in width and their extremities are slidably engaged with the extremities of the slots 98 in order to guide the movement of the lapping members. Each lapping element carrier 100 has a substantially axially extending outer surface 101 and an inner surface 102 which is inclined with respect to the longitudinal axis of the tubular casing 97, as viewed in Fig. 2. The lapping members are yieldably urged inwardly toward the center of the tubular casing 97 by springs 103 which are secured by screws 104 to the casing 97 and which have free end portions resiliently engaging the outer surface 101 of each lapping element carrier 100, respectively.

Slidably mounted on the interior of the tubular casing 97, and associated with each series of lapping element carriers 100 is a spreader member, generally designated by the numeral 105, which is adapted to uniformly urge all lapping elements of each series outwardly against the action of the springs 103. The spreader elements 105 are of generally cylindrical shape and they are provided with longitudinally extending slots 106 which are inclined with respect to its longitudinal axis for receiving the lapping element carriers 100. The bottom walls 107 of the slots 106 are inclined relative to the axis of the tubular casing 97 as to be parallel to the inclination of the inner surfaces 102 of the lapping element carriers 100. Formed in the periphery of the spreader member 105 are a plurality of arcuately spaced, substantially semi-cylindrical grooves 108 which are provided to reduce the

surface area contact between the spreader and the inner cylindrical surface of the tubular casing 97. Between the grooves 108 are ribs 109 which have outer extremities conforming in curvature to the cylindrical contour of the inner periphery of the casing 97. These rib extremities therefore provide substantial surface contact between the inner cylindrical surface of the casing 97 and the spreader element 105 throughout substantially the entire length of the latter so as to accurately pilot the spreader member within the casing 97 and to prevent relative radial movement of the spreader with respect to the casing. By virtue of this construction the outer working surfaces of the lapping elements 99 are accurately held in parallel relationship with respect to the axis of the casing 97, while the lapping elements are disposed in their various differently spaced relationships from the axis of the casing.

Apparatus for adjustably positioning the lapping elements 99 radially of the casing 97 is illustrated in Figs. 1 to 5, inclusive. This apparatus comprises an adjusting bar 111 disposed centrally of the interior of the casing 97 and extending substantially throughout the entire length thereof so as to simultaneously operate upon the spreader member 105 of each of the longitudinally spaced series of lapping elements 99 respectively. The left end of the rod 111, as viewed in Fig. 2, is non-rotatably secured to a cross head member 112 slidably mounted within the casing 97 by a pin 113. The cross head member 112 is provided with a diametrically extending passage 113 in which a pin 114 is disposed. The pin 114 has reduced end portions 115 which extend outwardly beyond the exterior surface of the casing 97 through axial slots 116 formed therein. The pin 114 has its end portions slidably engaged in helical slots 116 formed in a collar 117 surrounding the casing 97. Rotative movement of the collar 117 relative to the casing 97 while the collar is held against axial movement in the casing, as hereinafter set forth, causes the rod 111 and cross head 112 to be shifted axially of the casing 97 by reason of the camming action provided between the outer periphery of the end portions of the pin 114 and the side walls of the slots 116.

Provided on the exterior of the left end portion of the casing 97 is apparatus for releasably holding the collar 117 against movement axially of the casing 97 while accommodating rotative movement thereof relative to the casing. The collar 117, pin 114 and cross head 112 as well as the bar 111 are moved in unison axially of the bar. The collar 117 is concentrically mounted on the outer periphery of the casing 97 and its helical slots 116 receive bushings 118 in which the reduced end portions 115 of the pin 114 are received. The bushings 118 are held in assembled relationship on the reduced end portions 115 by screws 119 threaded in apertures formed in opposite extremities of the pin 114. Non-rotatably mounted on the collar 117 is a sleeve 120 which is secured to the collar 117 by rivets 121. The sleeve 120 has an inwardly extending radial flange 122 on its right extremity, as viewed in Fig. 2, which is spaced axially from the right extremity of the collar 117. Threaded on the left end portion of the casing 97 is a collar 123 having an outwardly extending radial flange 124 disposed between the inwardly extending flange 122 of the sleeve 120 and the right extremity of the collar 117, as viewed in Fig. 2. Interposed between the

extremities of the collar 117 and the collar 123 is a thrust bearing member 125. The collar 123 is provided with recesses 126 for receiving lugs of a spanner wrench by which the threaded collar 123 may be turned relative to the casing 97 in order to shift the collar 117 and the pin 114 as well as the cross heads 112 and the rod 111 in either direction axially of the casing. A locking ring 127 is also threaded on the left end portion of the casing 97 and located adjacent the right extremity of the collar 123 for the purpose of securely fixing the collar 123 against unintended rotation relative to the casing. When the locking ring 127 is released, the threaded collar 123 may be turned in either direction to shift the adjustment bar 111 axially in respectively corresponding directions. This adjustment varies the limit of expansion and contraction of the lapping stones which may be produced by rotation of the collar 117 relative to the casing 97.

A stop 128 is fixed on the adjusting bar 111 adjacent the right extremity of each spreader element 105 and is secured to the bar 111 by a pin 129. A stop 130 is mounted on the adjusting bar 111 in spaced relation to the right end of each spreader element 105, as viewed in Fig. 2, and secured to the bar by a pin 131. Interposed between the right extremity of each spreader element 105 and the associated stop 130, respectively, is a coil spring 132 by which the spreader elements are yieldably urged leftwardly, as viewed in Fig. 2, toward the stops 128. In this manner, the lapping elements of all of the longitudinally spaced series thereof are yieldably urged outwardly by the inclined surfaces 107 of the spreader element 105. The limiting outward positions to which the lapping elements 99 may be moved by the spreader elements 105 may be selectively predetermined by adjustably positioning the stops 128 and 130 by releasing the locking ring 127 and moving the collar 117 and rod 111 axially in the foregoing manner. Thus, when the lapping tool is inserted in an undersized bore, the lapping elements may be contracted by turning the collar 117 relative to the casing 97 so as to become accommodated to the bore and during the lapping operation the lapping elements are gradually moved outwardly as the diameter of the bore is increased to accommodate such outward movement until the left ends of the spreader elements 105 engage their respective stops 128 which prevent further outward movement of the lapping elements and thereby facilitate accurate predetermining of the diameter of the cylindrical bore operated upon. The collar 117 may be rotatively adjusted during operation of the tool in any suitable manner such as by functionally retarding or increasing rotation of the collar as the tool is rotating.

A lapping tool of the foregoing character may operate simultaneously upon a plurality of spaced bores such as are presented by the main bearings of a multiple cylinder internal combustion engine cylinder block, or if desired the lapping tool may comprise only one series of arcuately arranged lapping elements of any desired length which may be employed to lap a single cylinder bore such as the cylinder bore of a cylinder block. Internal cylindrical surfaces are accurately formed to true cylindrical contour while the working surfaces of the stones are accurately held in cylindrical arrangements and they are rigidly held against vibratory or other displacements by the relatively large piloting surfaces presented by the interior of the tubular casing 97.

In order to facilitate convenient coupling of the lapping tool to an operating shaft of a lapping machine, there is provided at the left extremity of the tool a universal type of coupling mechanism comprising a connecting shaft 133 having a ball 134 on its right end, as viewed in Fig. 2, which is disposed within the left end portion of the casing 97 and swivelled in a cylindrical block 135 which is splined in the interior of the casing. The block 135 has a diametrically extending passage 136 in which the end portions of a pin 137 extending through the ball 134 are disposed. The block 135 is held against outward displacement from the casing 97 by a threaded collar 138. Provided on the outer extremity of the shaft 133 is a knob 139 having a pin 140 extending therethrough by which the shaft 133 may be conveniently detachably connected with the final driving shaft or member of a lapping machine. Although but one specific embodiment of the invention is herein shown and described, it will be understood that various changes in the size, shape and arrangement of parts may be made without departing from the spirit of my invention.

What I claim is:

1. An expandable lap comprising a tubular casing having a plurality of circumferentially spaced openings therein, a lapping element carrier slidably mounted in each opening respectively and movable toward and away from the longitudinal axis of said casing, each of said lapping element carriers having an inner surface inclined with respect to said axis, a lapping element on the outer side of each carrier, means for adjustably positioning said lapping elements at divers distance from said axis including a cam member having a passage therethrough shiftably axially of said casing and having end portions guided by the internal surfaces thereof located at opposite extremities of said openings and having tapered portions cooperating with the inclined inner sides of said carriers for adjustably positioning the latter at divers distance from the exterior of said casing, a shiftable control bar extending through said passage of said cam member having an abutment located beyond one extremity of the latter, resilient means bearing between said abutment and the adjacent end of

said cam member for urging said member axially of said casing toward a position corresponding to the maximum outward positions of said lapping elements, a stop on said control bar located beyond the opposite end of said cam member for positively limiting movement of said member by said resilient means, and an adjustable member on said casing operatively connected with said bar for selectively positioning said stop and abutment at diverse locations.

2. A multiple expandable lap comprising a cylindrical tube having axially spaced series of circumferentially arranged slots therein, a lapping member shiftably mounted in each slot and movable toward and away from the longitudinal axis of said tube, lapping element spreaders axially shiftably mounted in said tube, one associated with the lapping members of each of said series of slots respectively, an adjustable control member axially shiftably mounted in said tube and movable axially relative to said spreaders, stops on said control member for selectively positively limiting movement of said spreaders toward positions corresponding to maximum outward positions of said lapping members, and a spring acting between said control member and each spreader respectively normally urging the latter toward its associated stop.

3. A multiple expandable lap comprising a hollow tube having axially spaced series of circumferentially arranged slots therein, lapping members shiftably mounted in said slots and movable toward and away from the longitudinal axis of said tube, lapping element spreaders axially shiftably mounted in said tube, one associated with the lapping members of each of said series of slots respectively, an adjustable control member shiftably mounted on said tube and movable axially relative to said spreaders, stops on said control member for limiting movement of said spreaders in the direction of movement thereof which causes expansion of said lapping members, a spring bearing between said control member and each spreader respectively for normally urging the latter toward its associated stop, and means coacting between said hollow tube and said control member for releasably holding the latter in a selected position.

DAVID A. WALLACE.
